(57) **CLAIM**

The ornamental design for a medical rongeur, as shown and described.

DESCRIPTION

FIG. 1 is a perspective view of the medical rongeur;

FIG. 2 is a left side view thereof;

FIG. 3 is a right side view thereof;

FIG. 4 is a top side view thereof;

FIG. 5 is a bottom side view thereof;

FIG. 6 is a front side view thereof; and,

FIG. 7 is a rear side view thereof.

1 Claim, 5 Drawing Sheets---
